HAIR CURLER

Lawrence J. Hall and May Ruth Hall, Middletown,
N. Y., assignors to Damosei, Inc., a corporation
of New York

Application June 25, 1946, Serial No. 679,093

1 Claim. (Cl. 132—42)

1

This invention relates to a hair curler.

An object of the invention is the provision of a hair curler embodying improvements in construction whereby the curler enables a hair curling operation to be carried out quickly and easily, which is comfortable to the user, and which is easy on the hair.

The invention also resides in the simplicity of the construction, the economy with which it may be produced, and the general benefits derived therefrom.

The nature of the invention and its distinguishing features and advantages will appear when the following specification is read in conjunction with the accompanying drawing, in which—

Fig. 1 is a perspective view of a hair curler embodying the features of the present invention shown closed on the hair to curl the same.

Fig. 2 is a transverse sectional view taken on the line 2—2 of Fig. 1.

Fig. 3 is a perspective view of the curler shown open and the hair inserted between the closed curling members for the hair curling operation, one of the curling members being shown in open position in dotted lines.

Fig. 4 is a transverse sectional view taken on the line 4—4 of Fig. 3.

Fig. 5 is a longitudinal sectional view of the curler shown open.

Fig. 6 is a longitudinal sectional view of the curler shown closed.

Fig. 7 is a longitudinal sectional view illustrating how two similar main parts of the curler may be produced from a single piece of material.

Fig. 8 is a side view of one of the parts of the curler.

In accordance with the present invention the curler comprises two parts 10 and 11, respectively. Each of said parts is made entirely of flexible resilient or elastic material such as rubber.

The part 10 of the curler is economically produced from a rubber tube of suitable length and diameter. By cutting the tube with a suitable cutter while the tube is pressed flat two similar parts 10 are produced in one and the same operation, as indicated in Fig. 7. The part 10 is concavo-convex in cross section a portion of its length providing a hair curling member 12 of the mentioned cross-sectional shape. The remain-

2

ing strip portion 13 of the part 10 constitutes a flexible or bendable securing means having a resilient or elastic terminal loop 14.

The part 11 consists of a rubber tube approximately one half the length of the main part 10. This tube has an outside diameter approximately equal to the inside diameter of the tube from which the main part 10 was cut. The part 11 is notched as at 15 to provide a resilient or elastic band or loop 16 on one end of the part 11. The part 11 constitutes a cylindrical curling member which is adapted to cooperate with the member 12 in curling the hair.

The two parts 10 and 11 are correlated by rolling the curling member 12 longitudinally and then slipping the band or loop 16 along the rolled member 12 to a point intermediate the ends of the part 10 or at the juncture of the member 12 and the strip portion 13, as shown most clearly in Figs. 3 and 5. In this manner the curling member 11 is connected with the main part 10 for pivotal movement with respect to the curling member 12 into an open position to enable the insertion of the ends of a strand of hair between said members, as indicated in Figs. 3 and 4, and for movement into a closed position, as indicated in Figs. 3 and 5. The curler then may be rotated to wind the hair spread out around both members 11 and 12. The securing means 13 is then folded or bent back over the curl and the loop 14 is engaged around the outer projecting end 11 of the member 11, thereby retaining the hair curled on the curler and also retaining the curler in place on the hair close to the skull of the user, as indicated in Fig. 1.

The parts of the device being soft and resilient will be comfortable to the user and easy on the hair. Also, the parts may be produced economically as will appear from Figs. 7 and 8 and by the mere act of slipping the loop 16 along the part 10 the curler is made complete for sale and use.

We claim:

45 A hair curler comprising two parts each of which is made entirely of rubber, one of said parts being concavo-convex in cross section, a portion of its length providing a hair curling member and the remaining portion constituting a securing member, the second of said parts constituting a hair curling member, and having a loop formed integral with one end and engaged with the first

part intermediate the ends of the latter so that the second part may be moved with respect to the concavo-convex part into an open position to enable the insertion of the ends of the hair between said second part and the concavo-convex part and also moved into a closed position to enable the hair to be curled about said second part and the concavo-convex part, said securing member engageable with said second part to retain the hair curled and also to retain the curler 10 in place on the hair.
